WILLIAM F. SCHMIDT, OF DETROIT, MICHIGAN.

POP-GUN.

1,179,967.

Specification of Letters Patent. Patented Apr. 18, 1916.

Application filed March 15, 1915. Serial No. 14,478.

To all whom it may concern:

Be it known that I, WILLIAM F. SCHMIDT, a citizen of the United States, residing at Detroit, county of Wayne, State of Michigan, have invented a certain new and useful Improvement in Pop-Guns, and declare the following to be a full, clear, and exact description of the same, such as will enable others skilled in the art to which it pertains to make and use the same, reference being had to the accompanying drawings, which form a part of this specification.

This invention relates to pop guns and has for its object a pop gun which forces a cork or other plug out of the end of the barrel and which is provided with means for reliably returning the cork or plug into the end of the barrel when the gun is broken.

In the drawings,—Figure 1 is a side elevation of the pop gun after it has been discharged. Fig. 2 is a similar view showing the gun being broken for the purpose of putting the spring under compression. Fig. 3 is an enlarged longitudinal section of the gun adjacent the end of the barrel, showing the position of the parts after the gun has been discharged. Fig. 4 is a similar view showing the position of the parts when the gun is being broken. Fig. 5 is an end view 30 of the sleeve or guide that fits on to the end of the barrel, the right hand side of this view being a section. Fig. 6 is a side elevation of the parts adjacent the end of the barrel showing how the sleeve or guide is removable.

The gun is the ordinary pop gun with a stock *a* and a barrel *b* which may be broken as shown in Fig. 2 for the purpose of compressing the spring *c* that operates the piston *d*.

My invention consists in applying to the end of the barrel an extension, preferably in the form of a slotted sleeve or guide *e*. This is really an extension of the barrel and might be formed as an integral continuation of the barrel but I preferably make it removable as shown in Fig. 6, holding it on to the barrel by a slip joint.

A slide *f* in the form of a disk with a pair of projecting ears *g* that protrude through the slots of the sleeve, is adapted to be slid back and forth within the sleeve by the action of the rods *h*, which connect the slide with the stock of the gun above and forward of the pivotal point *i* of the stock.

I am aware that the use of rods of this

character in connection with pop guns is not new, but they have not been used to perform the functions that they are here used for. Here I use them for the purpose of picking up the cork or plug *j* and with the aid of the guide or slide, inserting the same in the end of the barrel, as shown in Fig. 2. This thrusting of the plug into the barrel is accomplished by the breaking of the gun. When the barrel has been broken and the stock and the barrel are swung toward the closing of the two, the slide *f* is caused to retreat from the plug until, when the barrel and stock are closed, as shown in Fig. 1, it occupies the position near the outer end of the sleeve. The gun may now be discharged and the plug travels outward in the sleeve until it strikes the slide *f*. This is sufficient to allow the air escaping behind the plug to make the usual pop noise which is the object of guns of this class. The stock acts as a lever to set the piston and spring for discharge.

From the above description it will be seen that the plug is automatically replaced and that not only is the inconvenience of losing the plug dispensed with but it requires no operation at all in the way of fitting the plug back into its place when it is desired to discharge the gun.

What I claim is:

1. In a pop gun, the combination of a barrel, a plug for fitting into the end of the barrel, means for discharging the plug from the end of the barrel, a stock pivoted to the opposite end of the barrel, and means operated by the breaking of the gun for returning the plug into the end of the barrel.

2. In a pop gun, the combination of a barrel, a stock pivoted thereto, a plug that fits into the free end of the barrel, means for discharging the plug from the barrel, means for guiding and restraining the plug when discharged from the end of the barrel, and means operated by the breaking of the gun for returning the plug with the aid of said guiding means to the end of the barrel when the gun is broken.

3. In a pop gun, the combination of a barrel, a lever pivoted thereto, a plug fitting into the end of the barrel, an extension or sleeve on the end of the barrel, means for discharging the plug from the barrel, said means being set for action by the operation of said lever, a slide running in said extension or sleeve, and rods connecting the said

slide with the lever so that the plug may be returned into the end of the barrel when the gun is set for discharge.

4. In a pop gun, the combination of a barrel, a stock pivoted thereto, a plug fitting into the end of the barrel, means for discharging the plug from the barrel, a slotted sleeve or extension on the end of the barrel, a slide guided in said sleeve or extension, and connecting rods connecting the slide with the stock of the gun so that when the gun is broken the plug is returned to the end of the barrel and the slide retreats, upon the gun being closed, to a position where it may allow the discharge of the plug.

5. In a pop gun, the combination of a barrel, a stock pivoted thereto, a plug that fits into the end of the barrel, means for discharging the plug from the barrel, a sleeve or extension on the end of the barrel provided with slots in its side, a slide adapted to be guided in the sleeve or extension, and rods connecting the slide with the stock forward of and above the pivotal point of the stock and barrel.

6. In a pop gun, the combination of a barrel, a lever pivoted thereto, a plug that fits in the end of the barrel, means for discharging the plug from the end of the barrel, a sleeve that removably fits upon the end of the barrel and is provided with slots in

its side, a slide guided in said sleeve, and connecting rods between the slide and the lever so arranged upon the lever that when the gun is set for discharge the slide carries the plug into the end of the barrel and when the lever resumes its initial position the slide retreats to allow the plug sufficient space in which to discharge.

7. In a pop gun, the combination of a barrel provided at its discharge end with an extension, a plug adapted to fit into the end of the barrel and the said extension being only slightly larger in diameter than the plug to guide the same, a spring and piston located in the barrel for compressing air, a lever provided with connections for retracting the piston and compressing the spring, a slide engaging in said extension of the barrel and ahead of the plug, and a connection between the slide and lever whereby when the lever is moved to retract the piston and compress the spring the slide is caused to move inward in said extension and force the plug into the end of the barrel.

In testimony whereof, I sign this specification in the presence of two witnesses.

WILLIAM F. SCHMIDT.
